UNITED STATES PATENT OFFICE

173,162

ROLLER FOR A PAINT ROLLER

Stephen Knapp, Jr., Cleveland Heights, Ohio

Application June 29, 1954, Serial No. 31,223

Term of patent 14 years

(Cl. D9--2)

To all whom it may concern:

Be it known that I, Stephen Knapp, Jr., have invented a new, original, and ornamental Design for a Roller for a Paint Roller, of which the following is a specification, reference being had to the accompanying drawings, forming a part hereof.

In the annexed drawings:

Fig. 1 is a perspective view of a roller for a paint roller embodying the ornamental design.

Fig. 2 is a development of the roller showing the full surface of the roller shown in Fig. 1.

This application is a continuation-in-part of my co-pending applications Ser. Nos. D. 27,475 filed November 6, 1953, and D. 28,134 filed December 21, 1953, which are now abandoned.

I claim:

The ornamental design for a roller for a paint roller, substantially as shown and described.
